UNITED STATES PATENT OFFICE.

ALECK PRZYBYLEK, OF NEWARK, NEW JERSEY.

COMBINED KNIFE AND FORK.

1,324,565.

Specification of Letters Patent.

Patented Dec. 9, 1919.

Application filed August 23, 1919. Serial No. 319,831.

To all whom it may concern:

Be it known that I, ALECK PRZYBYLEK, residing at Newark, county of Essex, and State of New Jersey, have invented certain new and useful Improvements in Combined Knives and Forks, of which the following is a specification.

This invention has for its object the provision of an implement for cutting food and 10 conveying the same to the mouth, the implement being capable of operation by one hand.

A further object is to provide an implement of the class described capable of practical use by the lame, maimed or those having the use of one hand only, whereby food may be divided and manipulated in a convenient manner.

These objects are attained by the novel 20 construction and combination of parts hereinafter described and shown in the accompanying drawings, forming a material part of this disclosure, and in which—

Figure 1 is a front elevational view showing a combined knife and fork made in accordance with the invention, the cover plate being removed as indicated by line 1—1 of Fig. 2.

Fig. 2 is a side elevational view of the 30 same, parts being broken away in order to disclose the interior construction, and

Fig. 3 is a transverse sectional view taken on line 3—3 of Fig. 1.

Referring to the drawings in detail, the 35 numeral 10 indicates a hollow rectangular casing having a cover plate 11 engaged by screw bolts 12, the same passing through the opening in the casing and into the rear wall thereon.

40 A fork shank 16 is rigidly secured to the lower end of the casing with which is formed an offset extension 17 terminating in a plurality of prongs 18, the same being fashioned in the manner of an ordinary table fork.

Longitudinally slidable within the casing 10 is a rectangular plunger 19, having an offset upper portion 20, and joined by a stem therewith is an enlarged knob 21 adapted 50 to receive the thumb or finger of an operator whereby the plunger may be pressed inwardly against a compression spring 22 extending below the offset element 20 and guided by a pin 23 at its upper end, the 55 lower end encircling a pin 34, fixed in a lug 25 within the casing.

Formed with the plunger 19 is a rack bar 26, engageable with a spur pinion 27, one side of which is slidable against an abutment 28, formed with the cover plate 11, 60 while set centrally in the gear 28 is a pin 29, slidably and rotatably mounted in an elongated slot 30, formed in the rear wall of the casing 10 through which it extends.

The gear 27 is recessed interiorly and 65 provided with a plurality of internal ratchet teeth 31, and mounted in the recess is a disk 32, carrying a pawl 33, engageable with the teeth of the internal ratchet and held in position by a flat spring 34, the disk 70 being rigidly engaged with the spindle 29 upon which the gear 27 freely rotates.

Thus, as the knob 21 is depressed, rotary motion is transmitted by the rack and by reason of the pawl 33 to the disk 32, causing 75 the spindle 29 to rotate and move within the slot 30.

Rigidly engaged with the spindle 29 is a 80 knife blade 35, protected by a guard plate 36, attached at its upper end by an offset connection 37, to the casing 10 and in order to hold the knife blade when in a raised or covered position, a flat spring 38 is secured by riveting or the like in the interior of the casing, within the guard plate 36 and in 85 contact with the blade when in a folded position, thereby holding it yieldingly against movement.

In operation, when it is desired to use the 90 implement as a fork only, the casing and cover are grasped by the hand and the fork actuated in any desired manner.

When it is desired to use the knife, as in slicing foods, the fork is inserted in the food, the plunger knob 21 depressed, 95 thereby turning the blade outwardly and at the same time depressing the same so that as it passes closely adjacent to the tines of the fork, in a circular path, on the axis 29, as to cut whatever the fork may be engaged with, 100 and by repeatedly depressing the extending knob 21 the blade will again be received within the guard blade 36, or moved out again by further movement of the knob.

From the foregoing it will be seen that a 105 novel and commodious device has been disclosed whereby food may be cut by an operator in a convenient manner and conveyed to the mouth in the usual way, all of the several operations being controlled by one 110 hand only.

Having thus described my invention what

I claim as new and desire to secure by Letters Patent, is—

1. In a combined knife and fork, the combination with a hollow casing, and a cover therefor, of a fork rigidly extending from one end of said casing, a plunger bar mounted to move longitudinally in said casing means for normally holding said plunger bar in a raised position, a knife pivoted in said casing, a gear rotatable on the pivot of said knife, operative connections between said gear and the knife, means preventing a retrograde movement of the knife, and a rack bar formed with said plunger adapted 15 to actuate said gear.
2. In a combined knife and fork, the combination with a hollow casing, and a fork extending from one end thereof, of a plunger slidable longitudinally in said casing, means 20 for actuating said plunger, means for normally holding said plunger in a raised position, a rack-bar extending from said plunger, a gear engageable therewith, a ratchet contained within said gear, a spindle upon 25 which said ratchet is fixed whereby said

spindle may be rotated in one direction only, a knife blade secured to said spindle adapted to be rotated by the downward movement of said rack bar, and a guard for said knife blade overlying said 30 casing.

3. In a combined knife and fork, the combination with a hollow casing, and a fork extending rigidly from one end thereof, of a plunger bar movable in said casing, means 35 for actuating said plunger bar, a rack formed with said plunger bar, a gear engaged with said rack, a spindle on which said gear rotates, a ratchet formed internally of said gear, a disk carrying a pawl 40 engageable with said ratchet, said disk being fixed upon said spindle, a knife blade secured upon said spindle, a guard extending from said casing forming a pocket for said knife blade, and a yielding contact secured 45 to said casing adapted to engage with said knife, when inclosed in said guard.

In testimony whereof I have affixed my signature.

ALECK PRZYBYLEK.
